UNITED STATES PATENT OFFICE

FREDERICK A. ANTON, OF TOPEKA, KANSAS

LATERAL ARM AWNING FOR STORE FRONTS

Application filed January 20, 1930. Serial No. 422,062.

This invention relates to store front awnings of the folding lateral arm type and my object more especially, is to provide appliances making provision for adjustments for insuring the support of each awning hanger in a vertical position, and to features for accurately setting each lateral arm to the pitch or incline desired for the awning when spread and for positively securing the arm against accidental shifting of position. Another object is to provide an awning fixture of simple, strong, durable and inexpensive construction, which can be expeditiously applied in operative position.

With these objects in view, the invention consists in certain novel and useful features of construction and combinations of parts as hereinafter described and claimed; and in order that it may be fully understood, reference is to be had to the accompanying drawings, in which:

Figure 1 is a side view of an awning hanger and lateral arm and cooperating elements for securing the hanger to the front of a building and the arm to the hanger, embodying the invention.

Figure 2 is a front view of the same with the lateral arm omitted.

Figure 3 is a section on the line III—III of Figure 1.

Figure 4 is an enlarged vertical section taken on the line IV—IV of Figure 1, but omitting the portion of the lateral arm disclosed by Figure 1.

Figure 5 is an elevational detail of one of the elements for securing the lateral arm to the hanger, said figure being on the scale of Figure 4.

Figure 6 is an inner face view on a smaller scale, of the bracket or element for the direct support of the lateral arm.

Figure 7 is an outer face view of an element for cooperation with the element shown by Figure 5 in securing the above mentioned bracket at the desired point of adjustment for holding the lateral arm at any desired pitch or incline.

Figure 8 is an inner face view of the element shown by Figure 7.

Figure 9 is a fragmentary front view of

the hanger, partly broken away, and the hanger being of slightly different construction from that shown in preceding figures, the figure also showing adjustment bolts of different structural form that are disclosed most clearly by Figure 3.

Figure 10 is a side view of the construction shown by Figure 9.

Figure 11 is a horizontal section taken on the line XI—XI of Figure 9.

Figure 12 is a detail perspective view of one of the adjustment bolts appearing in Figure 9.

Figure 13 is a top view of the adjustment bolt.

Figure 14 is a rear face view of the adjustment bolt.

Figure 15 is a fragmentary plan view of a U-shaped bracket for the direct support of the metal socket portion of the folding arm and the pivot of said socket portion.

Referring now to the drawings in detail, where like reference characters identify corresponding parts in all of the figures, 1 indicates one of a pair of hangers for fitting against the face of a building in a plane above the window thereof, and the hanger is provided with a forwardly-projecting arm 2 terminating in a horizontal head. Extending centrally through the upper end of the hanger and forming a pivotal suspension support therefor is a bolt 3, and projecting laterally from the back of the hanger at its lower end, is a pair of bifurcated lugs

4 through which extend headed clamping bolts 5. One of the bolts 5 also extends through the eye 6 of a horizontal bolt 7 extending through the web portion of the hanger, as shown most clearly by Figure 3, and a pair of nuts 8 engage said bolt and the opposite sides of the web portion of the hanger. Adjustment of said nuts effects swinging movement of the hanger to the right or the left until the same stands in a perfectly vertical position, and when this position is attained the bolts 3 and 5 are screwed home so that two of them shall clamp directly against the hanger, and the third shall clamp the eye portion of bolt 7 against the

100

hanger, the three bolts thus serving to secure the hanger firmly in position.

It is customary in practice where a metal beam or transom bar is secured in the front of a building, to provide properly spaced openings therein for the securing bolts for the awning support, and it has been found that occasionally corresponding bolt holes in a hanger will not properly register with such holes in the beam or if they do it may be found that the hanger is not occupying an exactly vertical position. With the construction above described it will be apparent that the provision of large openings or horizontal bifurcations in and at opposite sides of the hanger will permit of a slight swinging adjustment of the latter and thus permit the bolts to be utilized in clamping the hanger firmly in the position desired. The above arrangement however in order to guard against accidental swinging slippage of the hanger, possibly because of the bifurcations or elongated openings for the bolts, makes provision through the use of the bolt 7 and nuts 8, to anchor the hanger on one of the fixed bolts, against such lateral slippage, in a very simple and effective manner.

The cylindrical head of the hanger is provided with a horizontal transverse bore 9 which is of double conical form, that is tapers inwardly from each end as at 9. The lower part of the head is attenuated as compared with its upper part (see Figure 2) so that the lower portion of the head, indicated at 10, shall be relatively narrow. The bracket is formed below the head and in the attenuated portion mentioned with a transverse opening 11 below the narrow portion 10 of the head, and back of said portion, the web is formed with a flanged opening 12.

A bolt 13 extends rearwardly and centrally through the attenuated portion of the hanger below the head thereof, through the opening 11 and into the opening 12, and within the latter is engaged by a retaining nut or the like, and the bolt bears a journaled or swivelled relation to the hanger so that when turned it shall have no endwise movement, and threaded upon said bolt 50 within the opening 11 is a collar or nut 14 provided at its opposite sides with cylindrical trunnions 15.

Fitting snugly within the conical bore of the head at one side, is a conical clamping element 16 having a peripheral flange 17 bearing against the opposing side of the head of the hanger. Said element is tubular and its inner bore is reversely tapered relative to its outer surface, the smaller end 60 of the bore being adapted to snugly accommodate a pivot clamping bolt hereinafter mentioned, and the inner end of the clamping element 16 is provided with diametrically opposite notches 19 and said element is provided with a depending lug 20

fitting partly in the opening 11 adjacent the narrow portion 10 of the head, and said lug is provided with an opening 21 in the horizontal plane of the bolt 13.

A clamping element 22 in opposition to clamping element 16 is of conical form and fits snugly in the opposite side of the head 2 and is provided with diametrically opposite tongues 23 engaging the notches 19 of element 16 to insure proper relation of said elements when applied to the hanger head, and said clamping element 22 is provided with a depending lug 24 slightly wider than the opening 11 so as to bear against the attenuated portion of the hanger head. The lug 24 has a projecting portion 25 to fit into the opening 11, and extending through said projecting portion is an opening 26 in alignment with the opening 21 of lug 20 of clamping element 16, said opening 26 being adapted to receive the other trunnion of the collar or nut 14, as shown clearly in Figure 4, the arrangement being such that the turning of the bolt 13 in one direction or the other shall effect forward or rearward movement thereon of the nut or collar 14, as shown clearly in Figure 4, the arrangement being such that the turning of the bolt 13 in one direction or the other shall effect forward or rearward movement 90 thereon of the nut or collar 14 and thereby, through the trunnions of the latter, effect rotatable adjustment of the two clamping elements, and in this connection it will be noted that the interlocking of the body portions of said clamping elements together through the engaging tongues 23 and notches 19, is primarily for the purpose of automatically alining the openings 21 and 26 for engagement by the trunnions of the nut or collar 14, and thus facilitate the operation of setting up the awning. The lug 24 is provided in its outer face with a recess divided by a pair of central ribs or partitions 27 into a pair of similar chambers 28.

A U-shaped bracket 29 fits against one side of the hanger head and the corresponding end of the clamping element 22 and is provided with a conical boss 30 fitting snugly in and projecting through the clamping element 22 and into the clamping element 16, and is also provided at its lower end with a plurality of radial ribs 31, three being shown. The engagement of the middle and rearmost ribs 31 with the respective recesses 28 of lug 24 of clamping element 22 holds the U-shaped element in a certain position relative to said clamping element. If a different relative position is desired, the said parts should be fitted together with the middle and front ribs 31 engaging said recesses 28. This arrangement is adapted to set the arm, hereinafter identified, to dispose the awning at a greater pitch or incli-

nation than the first named adjustment. It will thus be apparent that the parts are adapted for use with all so-called lateral arm awnings, regardless of the extent of projection thereof beyond the building line.

The boss 30 of the U-shaped bracket is provided with a central bore enlarged at its outer end to form an angular socket 32 to accommodate the head of a horizontal pivot and clamping bolt 33 extending through said boss and the clamping member 16, and mounted upon the threaded end of the bolt is a nut 34 bearing against exposed face of the clamping element or member 16 so as to clamp the same and the U-shaped frame firmly together, and thus relieve the adjusting bolt 13 of that duty after the parts have been disposed in their final working positions. It will be apparent that quick and relatively wide adjustments are effected through the interlocking relation between the U-shaped bracket and the clamping member 22, and that the final fine adjustment necessary to insure the exact pitch of the awning desired, is effected through adjustment conjointly of the two clamping members or elements and the U-shaped bracket, and after such final adjustment is effected through the operation of the bolt 13, the nut 34 is screwed home tightly so as to relieve the bolt 13 of unnecessary strain, as above stated.

The U-shaped bracket carries a substantially vertical pivot bolt 35 extending through the metal socket portion 36 of the lateral folding arm customarily employed in this type of awning support. The head of the pivot bolt 35 is provided with a peripherally notched enlargement 37, and a dog or detent 38 is secured to the U-shaped bracket and adapted to engage one of the peripheral notches of said enlargement, and at the same time overlap said enlargement so that the pivot bolt 35 may be retained in position without using any retaining device at its lower end, such as a nut, cotter or the like. A spring for unfolding the folding arm is mounted on the pivot bolt and secured thereto at one end and at the other end bears against the arm. This construction is not disclosed in this application, as it is covered by one of my applications now pending, it being desirable to state however in this connection that the tension of the spring can be varied by the turning of the pivot bolt, and held at the desired tension by engagement of the dog or detent with the notched periphery of the enlargement of the head of said pivot bolt. This feature is not detailed in this application, as it also forms a part of the application hereinbefore mentioned. Furthermore the particular mounting of the arm on the U-shaped bracket has nothing to do with the construction whereby the U-shaped bracket is

adjusted rotatably and secured at any desired point in such adjustment.

As the various adjustments have been set forth in connection with the description of the construction of the device, it is not deemed necessary to recapitulate reference to the operation whereby the pitch of the arm may be varied or whereby the vertical position of the hanger shall be secured.

Figures 9 to 14 inclusive, illustrate a construction for securing the hanger in position, which in principle, corresponds to that appearing most clearly in Figure 3, except that through a wedge or cam action, the bolt which by adjustment laterally anchors the hanger against lateral shifting, and also serves to apply rearward clamping pressure on the hanger.

In sheet 2, the front face of the back wall of the hanger is provided with vertically spaced horizontal ribs 39, one above and the other below the respective bifurcation 4, and the front face of the back wall between said ribs tapers or slopes outwardly as at 40, and the web of the hanger is provided with a pair of openings 41, one above and the other below and at equal distances from the horizontal plane of the center of the bifurcations.

Fitting slidably through the respective openings 41 are angle-bolts 7a corresponding to bolts 7, and said bolts project inwardly respectively from the inner ends of perforated heads 8a fitting snugly upon the bolts 5. In this case, the bolt heads 8a taper inwardly to correspond with and flatly fit the tapered faces 40 of the hanger. In other words, the heads 8a constitute wedges between the tapered faces of the back wall of the hanger and the heads of bolts 5, so that inward adjustment of bolts 7a shall cause their respective heads to apply rearward clamping pressure on the hanger, it being noted that the front faces of the heads 8a are parallel with the rear or untapered face of the back wall of the hanger and the rear sides of the heads of bolts 5, so that the full area of the heads of the latter contact with and apply force flatly upon the heads 8a. The upper and lower edges of the heads 8a are parallel with and adjacent the opposing sides of the upper and lower ribs 39, so that the latter serve as guides for the heads 8a in their inward or outward sliding adjustments. The heads 8a also have elongated bosses 42 at their outer sides, slidably fitting the bifurcations 4, these bosses giving the heads 8a a relatively extended contact on the bolts 5, and of course, increase the strength and rigidity to the heads. It will be noted, in this connection that by equipping one of the bolts 7a with nuts at both sides of the hanger web, as bolt 7 is equipped in Figure 3, the other bolt 7a may be dispensed with. It is preferred

however to use the duplicate construction as illustrated on Sheet 2, using one bolt 8a, to effect adjustment of the hanger in one direction and the other to effect reverse adjustment of the hanger. Where two bolts 8a are employed, one is reversed relative to the other. It is therefore necessary, if the bolts 8a are of interchangeable construction, that the bolt shank shall be offset relative to the 10 longitudinal axis of the head, as shown. It will be seen that if the arm 36, when in folded position, sags or slopes downward toward its free end, it can be readily brought to a horizontal position by such adjustment of the bolt or bolts 8a, as shall effect proper lateral swinging adjustment of the respective hanger. If a pair of the bolts 8a are employed, it will be necessary of course, to adjust both, one to effect the swinging movement and the other to permit or accommodate such adjustment.

From the above description, it will be apparent that I have produced a lateral arm awning support which embodies the features of advantage set forth as desirable in the statement of the object of the invention and which may obviously be modified in minor particulars without departing from the principle of construction and mode of operation 30 involved or from the spirit and scope of the appended claims.

I claim:

1. In an awning, a hanger having a back wall and a forwardly projecting web, the 35 back wall having openings, headed securing devices extending through said openings, and means anchored to one of the securing devices and engaging the hanger web and operable to effect lateral adjustment of the hanger.

2. In an awning, a pivotally suspended hanger having a back wall provided with a pair of openings, and a forwardly projecting web, headed securing devices extending 45 through said openings, and means anchored to one of the securing devices and engaging the web and operable to effect lateral tilting adjustment of the hanger on its pivotal suspension point.

3. In an awning, a pivotally suspended hanger having an opening, a laterally-adjustable member carried by the hanger and provided with an opening opposite the opening of the hanger, and an element extending 55 through said openings and forming an anchorage whereby adjustment of the laterally-adjustable member shall effect lateral swinging adjustment of the hanger.

4. In an awning, a pivotally suspended hanger having an opening, a substantially horizontal bolt extending through the hanger and provided with an eye at one end registering with the said opening of the hanger, a nut on said bolt engaging one side 65 of the hanger, and a clamping bolt extend-

ing through the eye of the first-named bolt and the opening of the hanger and forming an anchorage for the former whereby adjustment of the said nut shall effect lateral swinging adjustment of the hanger and secure the same firmly in the desired position relative to the anchoring bolt. 70

5. In an awning, a hanger having a suspending opening and a pair of openings in a lower plane than and at opposite sides of the vertical plane of the suspending opening, headed bolts extending through the openings of the hanger, the heads of two of said bolts applying clamping pressure on the hanger, and means mounted on the hanger and relatively adjustable laterally of the latter and provided with a head through which the third of said clamping bolts extends and adapted to transmit clamping pressure from the head of said third bolt onto the 80 hanger to cooperate with the other pair of bolts in clamping the latter rigidly in position. 85

6. In an awning, a hanger having a transverse horizontal head, a bracket at one side of the head, means rotatably adjustable around the axis of the hanger head and forming a support for the bracket, a rotatable element on the hanger, and means actuated by turning movement of said element 95 for effecting adjustment of the said bracket support.

7. In an awning, a hanger having a transverse horizontal head, a bracket at one side of the head, means rotatably adjustable 100 around the axis of the hanger head and forming a support for the bracket, a rotatable element on the hanger, means actuated by turning movement of said element for effecting adjustment of the said bracket support, and means for interlocking the said support and bracket together in different radial relations. 105

8. In an awning, a hanger, a bracket rotatably adjustable on the hanger around a transverse horizontal axis, a swivelled element mounted in the hanger, a collar mounted on the swivelled element and movable back and forth by turning movement of the latter, and means whereby said collar in its movement 110 on the swivelled element shall effect rotatable adjustment of the bracket. 115

9. In an awning, a hanger, a bracket rotatably adjustable relative to the hanger around a transverse horizontal axis, a bolt in the hanger, a collar threaded on the bolt and provided with laterally-projecting trunnions, a pair of rotatably adjustable clamping elements mounted on the hanger and engaged by said trunnions, one of said elements forming a direct support for said bracket; and means establishing an interlocking relationship between one of said clamping elements and the said bracket for transmitting 120 125 130 135 140

rotatable movement from the former to the latter.

10. In an awning, a hanger having a transverse tubular head, a pair of clamping elements rotatably adjustable in said head, a bracket having a boss projecting into one of said clamping elements, a bolt extending axially through said boss and said clamping elements and provided with a head at one end and a retaining device at the other end for preventing separating movement of said elements and brackets; said elements having depending lugs and one of them bearing an interlocked relationship to said bracket, a bolt swivelled in the hanger between the said lugs, and a collar threaded on the bolt and provided with trunnions pivotally engaging the said lugs respectively.

11. In an awning, a hanger having a tubular transverse head, a pair of clamping elements fitting in said head from opposite sides thereof and one of them provided with a flange bearing against the opposing end of the head; one of said elements having a notch in its inner end and the other a tongue projecting into said notch, lugs depending from said clamping elements, a bolt swivelled in the hanger between said lugs, a collar threaded on the bolt and provided with oppositely projecting trunnions pivotally engaging said lugs respectively, a bracket at one side of the head and provided with a boss snugly fitting within one of said clamping elements, and interlocked as regards rotatable movement with one of the said lugs, and a bolt extending axially through said bracket and through said clamping elements and provided with a head at one end and a nut at the other end for clamping said elements and bracket together and to the hanger head.

12. In an awning, a hanger, a pair of clamping elements rotatably mounted upon the hanger and interlocked together as regards rotatable movement, one of said clamping elements having a lug, a bracket fitting against the clamping element provided with the lug, mutually engaging ribs on said bracket and lug for preventing rotatable movement of the bracket independent of said clamping elements, means carried by the hanger for effecting conjoint rotatable adjustment of the clamping elements and the bracket, and clamping means securing the bracket and the clamping elements in rigid relation to the hanger.

In testimony whereof I affix my signature.
FREDERICK A. ANTON.
